UNITED STATES PATENT OFFICE.

GEORGE R. PENN, OF NEW YORK, N. Y., ASSIGNOR TO S. R. PENN MFG. CO., OF NEW YORK, N. Y.

LOUD-SPEAKER UNIT.

Application filed September 30, 1926. Serial No. 138,695.

This invention relates to a loud speaker unit designed primarily for use with a cone diaphragm, one of the objects of the invention being to provide a unit so constructed 5 as to eliminate unnecessary vibrations and improve both the quality and volume of the tone.

A further object is to provide a unit the parts of which can be rapidly assembled in 10 quantity production.

A still further object is to provide simple and efficient means for regulating the volume, the said means being so mounted and constructed that danger of development of 15 loose connections is practically eliminated with the result that the desired tone can be maintained indefinitely.

Another object is to provide an adjustable support for the unit, thereby allowing the 20 same to be assembled with cone diaphragms of different sizes.

A further object is to provide a unit of this character which can be sold for installation by the purchaser in a cone speaker 25 of home-made construction.

With the foregoing and other objects in view which will appear as the description proceeds, the invention resides in the combination and arrangement of parts and in 30 the details of construction, hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a front elevation of the unit, 40 the cone diaphragm being removed.

Figure 2 is a side elevation, a portion of the cone being shown in section.

Figure 3 is a section on line 3—3, Figure 1.

Figure 4 is a rear elevation of the unit, 45 its supporting bracket being removed.

Figure 5 is a top plan view of the unit.

Figure 6 is a section on line 6—6, Figure 3.

Figure 7 is a front elevation of a slightly 50 modified form of unit.

Figure 8 is a section on line 8—8, Figure 7.

Referring to the figures by characters of 55 reference 1 designates the back of the loud speaker which can be in the form of a disk

of any suitable construction. Arranged on one face of this disk are spacing strips 2 provided with terminal ears 3 and 4, the ears 4 being in contact with the back 1. An elongated bolt 5 is extended through the back and through the ears 3 and 4 of each strip 2, it being understood that the number of these bolts is equal to the number of the spacing strips. A nut 6 engages each bolt and is adapted to be adjusted against the adjacent ear 4, thereby to tightly clamp the base 1 between the head 7 of the bolt and the ear 3. Thus the strips 2 are mounted firmly relative to the base.

The threaded end portions of the bolts 70 projecting beyond the ears 4 are each engaged by a pair of nuts 8 and mounted between and clamped by these nuts so as to be firmly supported by the bolts at desired distances from the back 1 are the terminals 75 of a spider 9 formed preferably of insulating material and including a cross strip 10 and a central depending strip 11. A permanent magnet 12 is engaged at its center by a clip 13 which serves to hold it firmly to the strip 10 of the spider and mounted on the terminals of the fixed magnet are alining pole pieces 14 each preferably formed of a flat piece of metal supporting the coil 15 of an electromagnet. The two coils are electrically connected as indicated at 16 while the other terminals of the coils extend to any suitable connections indicated at 17 to which are attached the ends of the cord 18 extending to the unit. These connections 90 17 are carried by a block 19 of suitable insulating material preferably of skeleton form and which block is attached at its sides to the pole pieces 14 and to the terminals of the fixed magnet by bolts 20 extending through the block 19, the pole pieces, the terminals of the fixed magnet and the strip 10. Block 19 includes a bridge portion 21 which extends across the space between the terminals of the fixed magnet and 95 carried by this bridge portion is an abutment block 22 normally contacting with the free end portions of the pole pieces. Thus vibration of the pole pieces during the operation of the unit is prevented and many 100 of the undesirable noises heretofore produced in units employing relatively thin pole pieces, are eliminated.

A spring strip 23 extends transversely of the block 19 and is secured at its ends to 110

opposite side portions of this block. Extending outwardly from the middle portion of the spring strip is a sleeve 24 the outer end of which is interiorly screw threaded so as to receive a tubular screw plug 25 in which is mounted an adjusting screw 26 extending longitudinally within the plug. This adjusting screw has a head 27 by means of which it can be rotated readily and a set screw 28 extends into the plug for the purpose of binding on the adjusting screw 26 to hold it against accidental rotation.

Secured to the middle portion of the block 19 adjacent the bottom thereof is one end of a spring strip indicated at 29 and this strip is extended through the block and thence close to and in lapped relation with the free end portions of the pole pieces 14. This spring strip constitutes the armature of the magnet and normally bears against one side of the pole pieces while the other side of the pole pieces normally engages the abutment block 22 as heretofore explained. A push rod 30, preferably in the form of a stiff wire, is fixedly attached to the armature at a point close to the pole pieces and is mounted to slide within the sleeve 24 and the screw plug 25. Thus when the parts are properly assembled the rotation of adjusting screw 26 in one direction will result in pressure by said screw against rod 30 and consequent adjustment of the armature away from the pole pieces. The extent of vibration of the strip 23 and the parts carried thereby will depend upon the distance that the armature is adjusted away from the pole pieces. A diaphragm 31 preferably of cone-shape is detachably secured to the sleeve 24, its apex portion being preferably clamped between small disks 32 and 33 mounted on the screw plug and clamped firmly to the sleeve 24 by said plug.

It will be obvious that, as the armature vibrates, vibratory motion will be transmitted therefrom through the rod 30 to screw 26 and thence through sleeve 24 to spring strip 23. Thus the diaphragm will be vibrated. By having the set screw 28 the parts can be held securely after adjustment so as not to work loose and cause inadvertent change in quality or volume of tone.

For the purpose of adapting the unit to cone diaphragms of different sizes and shapes, the unit has been mounted on the bolts 5 as already explained, the nuts 8 serving to hold the spider 9 firmly at a desired distance from the back 1. Obviously these nuts can be adjusted toward or from the strips 2 so as to locate the unit closer to or farther from the back according to the size of tone diaphragm employed. This mounting of the unit is especially desirable in cases where units are sold to customers who make their own cone diaphragms, it being possible to use the same unit with cones of all sizes.

Instead of mounting the armature as already described, a slightly modified arrangement can be used as illustrated in Figures 7 and 8. In this form of device the insulating block 19' has a spring strip 34 secured at its ends to opposed portions of the block. The sleeve 24' is extended from the upper portion of the spring strip while a spacing sleeve 35 is extended in the opposite direction from the lower portion of the spring strip and is fixedly attached thereto. One end of the spring armature 36 is attached to this spacing sleeve while the other end portion has a push rod 30' extending from it into the sleeve 24'. In all other respects this modified structure is the same as the one heretofore described. In other words the modified arrangement differs from the preferred form by the provision of an armature supported solely by the spring strip carrying the diaphragm.

What is claimed is:

1. A loud speaker unit including a permanent magnet, pole pieces extending from the terminals thereof, coils mounted on the pole pieces, an armature close to but normally spaced from the pole pieces at one side, and an abutment normally engaging the opposite side of the pole pieces for limiting their movement under the pressure of the armature when attracted to the pole pieces.

2. A loud speaker unit including a permanent magnet, flat pole pieces extending from the terminals thereof, electromagnet coils carried by the pole pieces, an abutment of non-conducting material normally contacting with one side of the pole pieces, an armature normally positioned adjacent but spaced from the other side of the pole pieces, a resiliently mounted diaphragm support, and means adjustably connected to said support for adjusting the armature away from the pole pieces.

3. A loud speaker unit including a permanent magnet, opposed alining pole pieces extending from the terminals thereof, electromagnet coils carried by the pole pieces, an armature close to but normally spaced from one side of the pole pieces, a resilient diaphragm supporting structure, an adjusting screw carried thereby, a thrust element for transmitting motion from the screw to the armature, and means for holding the screw against accidental rotation.

4. A loud speaker unit including a magnet having opposed alining pole pieces at the terminals thereof, electromagnet coils carried by the pole pieces, a resilient armature close to but normally spaced from one side of the pole pieces, an abutment normally engaging the other side of the pole pieces, a diaphragm supporting structure, and an adjustable thrust connection between said structure and the armature.

5. A loud speaker unit including a mag-

- net having opposed alining pole pieces at the terminals thereof, electromagnet coils carried by the pole pieces, an armature normally spaced from and movable relative to one side of the pole pieces, an abutment of non-conducting material normally engaging the other side of the pole pieces, a resilient diaphragm supporting structure, and an adjustable thrust connection between said structure and the armature.
6. The combination with a back and a diaphragm supported close to the back, of threaded members fixedly connected to the back, a structure adjustably mounted thereon, a loud speaker unit carried by said structure, and a connection between said unit and the diaphragm, said diaphragm cooperating with the back to house the unit and its supporting structure.
7. A loud speaker unit including a magnet having opposed alining pole pieces, electromagnet coils carried thereby, a block of insulating material bridging the magnet, an abutment carried by the block normally engaging one side of the pole pieces, an armature close to but normally spaced from the other side of the pole pieces, a resilient strip upon the block, means carried thereby for engaging and supporting a diaphragm, a push rod extending from the armature, and an adjusting element carried by the diaphragm supporting means for actuating the push rod to adjust the armature away from the pole pieces.
- In testimony that I claim the foregoing as my own, I have hereto affixed my signature.

GEORGE R. PENN.

net having opposed alining pole pieces at the terminals thereof, electromagnet coils carried by the pole pieces, an armature normally spaced from and movable relative to one side of the pole pieces, an abutment of non-conducting material normally engaging the other side of the pole pieces, a resilient diaphragm supporting structure, and an adjustable thrust connection between said structure and the armature.

6. The combination with a back and a diaphragm supported close to the back, of threaded members fixedly connected to the back, a structure adjustably mounted thereon, a loud speaker unit carried by said structure, and a connection between said unit and the diaphragm, said diaphragm co-operating with the back to house the unit and its supporting structure.

7. A loud speaker unit including a magnet having opposed alining pole pieces, electromagnet coils carried thereby, a block of insulating material bridging the magnet, an abutment carried by the block normally engaging one side of the pole pieces, an armature close to but normally spaced from the other side of the pole pieces, a resilient strip upon the block, means carried thereby for engaging and supporting a diaphragm, a push rod extending from the armature, and an adjusting element carried by the diaphragm supporting means for actuating the push rod to adjust the armature away from the pole pieces.

In testimony that I claim the foregoing as my own, I have hereto affixed my signature.
